United States Patent Office.

SAMUEL W. GIBBS, OF ALBANY, NEW YORK.

Design No. 2,560, dated January 22, 1867.

DESIGN FOR A COAL-SHOVEL.

The Schedule referred to in these Letters Patent and making part of the same.

TO ALL WHOM IT MAY CONCERN:

Be it known that I, SAMUEL W. GIBBS, of the city of Albany, in the county of Albany, and State of New York, have invented a new and original Design for a Cast-Iron Coal-Shovel, of which the accompanying drawing is a correct representation.

What I claim as my invention, and desire to secure by Letters Patent, is—

The design for a cast-iron coal-shovel as represented in the accompanying drawing.

S. W. GIBBS.
